Des. 185,154
Patented May 12, 1959

185,154

COMBINED BABY NIPPLE AND PACIFIER

Ervim Krol, Sao Paulo, Brazil

Application August 6, 1957, Serial No. 47,251

Term of patent 14 years

(Cl. D83—8)

Fig. 1

Fig. 2

Fig. 1 is a perspective lateral view of a combined baby nipple and pacifier showing my new design; and
Fig. 2 is a front elevational view thereof.

The essential features of my design reside in the portions shown in full lines.

I claim:

The ornamental design for a combined baby nipple and pacifier, as shown and described.
